TROTECHNISCHE FABRIK SCHMIDT & CO., GESELLSCHAFT M. B. H., OF BODENBACH,
CZECHOSLOVAKIA

ELECTRIC REFLECTOR LAMP

Application filed May 31, 1930, Serial No. 458,614, and in Czechoslovakia November 27, 1929.

The present invention relates to electric incandescent lamps fitted with reflectors in which the lamp bulb is adjustable along the axis of the reflector, and its object is to facilitate adjustment of the lamp bulb without lateral displacement relatively to the reflector, and also to facilitate exchange of the lamp bulb and examination of the lamp contacts.

These objects are attained by mounting the lamp socket to slide in the reflector sleeve, and making a known pin and inclined slot connection between the sleeve and a rotatable bush arranged between the reflector sleeve and the lamp socket, so that by turning a lever attached to the bush, the socket is moved axially in relation to the reflector.

It is preferable to attach the lamp socket rigidly to the battery holder and to make the latter of box form, so that it may be firmly guided in the lamp casing, and the electrical connection between lamp contact, battery pole and switch contacts may be maintained notwithstanding displacement of the lamp relatively to the reflector. The box form of battery holder also provides a convenient place for sockets for spare lamps.

The accompanying drawing shows a construction according to the invention, where Fig. 1 is an axial section of a lamp,

Fig. 2 is a view of the interior of its casing with the battery holder removed and its guide omitted,

Fig. 3 is a view of its battery holder seen from that side where the incandescent lamp and the spare lamps are arranged,

Fig. 4 is a detail of Fig. 2

With reference to the drawing the reflector 10 has a sleeve 11 as usual, in which is an inclined slot 12 ending in a groove 12' parallel to the axis through which a pin on the bush 13 may be introduced. Alternatively the slot may be cut in the bush and the pin may be on the reflector sleeve. The bush 13 fits the reflector sleeve and has attached to it a hand lever 14 projecting laterally out of the lamp casing 15. In the bush 13 fits the smooth cylindrical periphery

of the lamp socket body 16, so that the bush 13 may be turned relatively to the socket body 16 by the hand lever 14. The lamp 17 is screwed into the socket body 16 in the usual manner. The socket body 16 for the lamp is fastened to a box form battery holder 18 which is open on the side remote from the lamp 17 to receive the battery 19.

A spring 20 secured to the lid 21 of the casing tends to move the battery 19 and box 18 and the socket body 16 towards the reflector.

Mounted on the battery box 18 are two holders 22, 23 for spare lamps as shown in Fig. 3.

The spindle of the switch lever 24 carries a switch contact spring 25 by which the lamp may be connected as desired either to battery contacts or to an external supply from a dynamo connected to the terminal 26. The connections for this purpose form no part of the present invention and are therefore not explained in detail. All that matters as regards the present subject is that the battery box 18 establishes connection on the one hand between the contacts of the switch and both a battery pole and a lamp contact, and on the other hand between the other battery pole and the other lamp contact. To this end the battery box is fitted with insulated contact strips 27, 28 one connected to the lamp contact 29 and the other to one pole of the battery. The electrical connection between the other pole of the battery and the other lamp contact is effected by a battery contact strip making metallic connection with the socket body 16.

The electrical connection between both the terminal 26 and the conductor leading from the dynamo and the incandescent lamp is effected partly by the lamp casing to which a lamp pole is electrically connected through the intermediary of the battery box, and partly by a contact spring 30, which is insulated from the casing and extending to the switch.

After opening the lid 21 a battery 19 may be put into the battery box with its short terminal strip either to left or right as desired, and the lamp is then ready. The lamp

may be focused by turning the arm 14 the outer end of which is insulated from the lamp casing, and so moving battery box and the battery in the casing.

5 The socket body 16 may be made axially movable relatively to the battery box instead of being rigidly secured thereto, in which case the battery box does not share the movement of the lamp.

10 The hand lever 14 may be wholly within the lamp casing.

In order that the incandescent lamp may readily be brought into or out of the focus of the reflector as desired, a bolt 35 having a head 36 and a nut 37 (Figs. 2 and 4) is movably set in the slot in the casing through which the hand lever 14 passes. On loosening the nut 37 the bolt 35 may be moved into any desired position and secured there by tightening the nut. In this way the position of the hand lever 14 which brings the filament of the lamp into exact focus of the reflector may be established once for all, so that there is no need to find it by trial and error on each occasion of use.

Having now particularly described and ascertained the nature of my said invention and in what manner the same is to be performed, I declare that what I claim is:—

20 Claims:

1. An electric reflector lamp, comprising a reflector having a sleeve, a casing for the said reflector, a slot in said casing, an incandescent lamp adjustable along the said axis of the reflector, and means for adjusting the incandescent lamp along the said axis of the reflector, the said means comprising a bush mounted between the lamp socket and the reflector sleeve, a pin and inclined slot connection between the reflector sleeve and the said bush, the latter being immovable axially but rotatable with respect to the lamp socket, a hand lever secured to the bush and adapted upon actuation to move the lamp socket axially in relation to the said sleeve, the said hand lever projecting exteriorly of the casing, an adjustable abutment slidably mounted in the slot of the casing through which the hand lever passes, the abutment defining that position of the hand lever in which the lamp filament is in the focus of the reflector, and means tending to urge the lamp socket forwardly of the reflector, the said bush tending to resist said last mentioned means.

2. An electric reflector lamp comprising a reflector having a sleeve, a casing for the said reflector, a slot in said casing, an incandescent lamp adjustable along the axis of the reflector, and means for adjusting the said lamp along the said axis of the reflector, the said means comprising a lamp socket slidably mounted in the reflector sleeve, a bush mounted between the lamp socket and the reflector sleeve, a pin and inclined slot

connection between the reflector sleeve and the said bush, the latter being immovable axially but rotatable with respect to the lamp socket, a hand lever secured to the bush and adapted upon actuation to move the lamp socket axially relative to the reflector sleeve, the said hand lever projecting exteriorly of the casing, and an adjustable abutment slidably mounted in the slot in the casing through which the hand lever passes, and comprising a headed bolt and a nut, the said abutment defining that position of the hand lever in which the lamp filament is in the focus of the reflector, and a spring tending to move the lamp socket forwardly of the said reflector, the bush resisting this tendency.

In testimony whereof I affix my signature.

PAUL RATHMANN.
